UNITED STATES PATENT OFFICE.

WILLIAM DEUTSCHER, OF NEW YORK, N. Y.

ELECTRIC PROTECTIVE DEVICE.

1,271,861.

Specification of Letters Patent.

Patented July 9, 1918.

Application filed December 20, 1912. Serial No. 737,809.

To all whom it may concern:

Be it known that I, WILLIAM DEUTSCHER, a subject of the Emperor of Germany, and a resident of the borough of Manhattan, city, 5 county, and State of New York, have invented a new and useful Improvement in Electric Protective Devices, of which the following is a specification.

My invention relates to electric protective 10 devices of that type designed to give an electrically controlled warning signal when operated, or when the circuit is caused to be closed, by one unfamiliar therewith. It is designed to be placed upon or adjacent to a 15 door or other closure in connection with the opening of which the signal will be given unless certain manipulations are first performed in connection therewith by one familiar with the combination thereof. An- 20 other object of the invention is to cause a signal to be given in case the device is attempted to be operated by one unfamiliar therewith. In other words, the signal will be operated either by a mere opening of the 25 door, the signal device being unobserved, or by an attempt to actuate the signal device by one unfamiliar therewith even though the door be closed. I accomplished these ob- 30 jects by embodying in my signal system what may be termed a selective control.

In the following I have described, in connection with the accompanying drawings, one means of carrying out the principles of my invention, the features thereof being 35 more particularly pointed out hereinafter in the claims.

In the drawings Figure 1 is a vertical 40 sectional view along the line 1—1 of Fig. 2, on an enlarged scale, of one illustrative form of device embodying my invention, parts being shown in diagrammatic form; Fig. 2 is a front view of the device, full size, as it 45 will appear embedded in or adjacent to a door and Fig. 3 is a top view of a detail showing the connections and control at the hinge of the door.

Similar numerals of reference indicate similar parts throughout the several views.

In the drawings, 8 indicates a casing made 50 of any suitable non-conducting material, circular in shape and provided with a flange 9 by means of which, in connection with screws extending therethrough, the device may be affixed to the door or wall adjacent thereto. 55 10 is a plate closing the back of the casing and fastened to the casing in any suitable

manner (not shown). The depth of the casing and the proportions of the parts should preferably be such that the selective devices may be set or withdrawn and reset 60 from the back of the device, *i. e.* from inside the door or wall.

11 and 12 indicate rings of electrically conducting material separated by a non-conducting flange 13, preferably a part of 65 the casing 8, to which flange 13 the rings are fastened in any convenient manner (not shown). 14 is a disk of preferably non-conducting material carrying as a part thereof and attached thereto a conducting ring 70 15. Disk 14 and its ring 15 are free to have motion toward and away from ring 12.

Disk 14 carries slotted bosses or sleeves 16, 17 and 18 preferably of non-conducting material on which sleeves a disk 19, preferably 75 of non-conducting material, is slidably mounted, disk 19 carrying a conducting ring 20. 21 is a stationary ring of conduct- 80 ing material. Disk 19 is free to have motion toward and away from ring 21. Spring 25 keeps ring 15 normally in contact with ring 12 and spring 26 keeps ring 20 normally in 85 contact with ring 21. 27 is a disk of prefer- 90 ably non-conducting material loosely mount- ed on the pins which are fastened to the push-buttons hereinafter described and car- 95 rying a conducting ring 28. Disk 27 is free to have motion toward and away from ring 11. Spring 29 surrounding boss 30 on disk 27 and bearing against disks 14 and 27 tends 100 to keep ring 28 normally out of contact with ring 11. Push-buttons 2, 1 and 5 mounted in the front wall of casing 8 carry pins 31, 32 and 33 respectively. The push but- 105 tons bear loosely against the outer face of disk 27, while the pins project through disk 27 but are free therefrom as shown. Both the push-buttons and pins are of non-con- 110 ducting material. Each of the sleeves 16, 17 and 18 are provided with slots 34 and key- ways 35 opening therewith for the purpose hereinafter described. 36 and 37 are pins of non-conducting material mounted in sleeves 17 and 18 respectively, pin 36 car- 115 rying a finger 38 adapted to bear against disk 14 and pin 37 carrying a finger 39 adapted to bear against disk 19. Pins 36 and 37 are also provided with stops 40 and 41 respectively, adapted to bear against the outside of plate 10. Pins 36 and 37 are rev- oluble in sleeves 17 and 18 so that fingers 38 and 39 may be brought into registry with

slots 34 therein and locked by turning the fingers out through the slots. Pins 36 and 37 may be withdrawn from the device by reversing the operation described. The pins 5 may then be reinserted in sleeve 16 or any of the others which may be provided, the stops limiting the inward movement of the pins by contacting with the plate 10. Pins 36 and 37 are also shown as being of less 10 diameter than the openings in disk 27 through which pins 31, 32 and 33 project.

40 is a battery or other source of power having one pole connected in parallel with contact ring 12 and the conducting ring 20 15 on disk 19, the common wire 43 to said branches in parallel being provided with a switch 44, and the other pole connected in parallel respectively to contact ring 11 and bracket 45 adjacent to or mounted on the 20 door. 46 is an electromagnetically controlled bell in series with contacts 47, 48 and 49 and contact 50 on bracket 45 but insulated therefrom. Contact 47 is in electrical connection with the conducting ring 28 on 25 disk 27 through a suitable flexible conductor, contact 48 is in electrical connection with the conducting ring 15 on disk 14 through another suitable flexible conductor and contact 49 is in electrical connection 30 with contact ring 21. 51 is an electromagnetically controlled bell in parallel with bell 46 and located at a point distant from bell 46. 52 is a bell crank of conducting material pivoted in bracket 45 and adapted to 35 close the circuit between bracket 45 and contact 50 when turned on its pivot by spring 53 on door 54, the opening of the door causing spring 53 to turn bell crank 52 to make contact and the closing of the door to break 40 contact. Leaf springs 55 are provided to take in behind stops 40 and 41 to retain pins 36 and 37 in inoperative position after they have been depressed. They may be readily released when the device is to be 45 reset. Springs 55 may of course be omitted, in which case the fingers of the operator must hold the pins in depressed position while opening the door.

In Fig. 2 I have shown seven push-buttons numbered from 1 to 7 inclusive. Of course there may be any number of push-buttons more than one, preferably at least one of said push-buttons having no co-operating pin, similar to pin 36 or 37, adjacent 55 to the inner end thereof, and there may be any number of pins 36, 37 but at least one. If only one such pin 36 or 37 is used the disk 19 and its associated parts may be omitted. In the drawing the gaps between the pins 60 32 and 36 and between the pins 33 and 37 are shown as being of different widths due to the difference in lengths of the pins 36 and 37. This is not necessary, however, provided that the gap between the pins 36, 65 37 and the pins 31, 32 and 33 is in each in-

stance less than the distance between rings 28 and 11 so that each pair of contacts corresponding to the respective pins 36, 37 will be broken before contact is made between rings 28 and 11 as will appear hereinafter. 70

I shall describe the operation of the device the parts being set as shown in the drawings. If one familiar with the combination of push-buttons wishes to open the door without actuating the bells he depresses push-button 1, thus forcing pin 36 inward and causing the contact between ring 12 and the conducting ring 15 on disk 14 to be broken. He then depresses push-button 5, forcing pin 37 inward and breaking contact between ring 21 and the conducting ring 20 on disk 19. Although by the depressing of the push-buttons disk 27 may have been moved to cause its conducting ring 28 to contact with contact ring 11, 80 no current will flow, as there is no path for the current through the battery. The order in which the push buttons are operated is not material, the essential thing being that each one of the pins 36, 37 should be protracted from its normal position so that each of the return circuits to the battery will be broken before the door is opened, regardless of the order in which these operations are performed. 90

Now if one unfamiliar with the combination opens the door without actuating any of the push-buttons, a path will be established from one pole of the battery through bracket 45, contact 50, bell 46, bell 51, ring 15 on disk 14 and ring 12 to battery and through contact ring 21 and ring 20 to battery, switch 44 being closed, and the bells will sound. 100

If push-button 2 is depressed, ring 28 on disk 27 will be forced into contact with ring 11 and a path will be established from one pole of the battery through ring 11, ring 28 on disk 27, contact 47, bells 46 and 51, and back to battery as described above. The bells 46 and 51 will thus be actuated without 105 even opening the door, indicating that one unfamiliar with the combination is attempting to enter. As the path through ring 11 and ring 28 is in parallel with that through bracket 45 and contact 50, the bells will 110 sound also with the door open.

If only push-button 1 is depressed, ring 28 is caused to contact with ring 11 as before, the path through ring 15 on disk 14 is broken but that through ring 20 on disk 19 120 is not broken. Hence the path for the current is established and the bells sound.

If only push-button 5 is depressed, ring 28 is caused to contact with ring 11 as before, the path through ring 20 on disk 19 is 125 broken but that through ring 15 on disk 14 is not broken. Hence the path for the current is established and the bells sound.

It is obvious that the pins 36 and 37 may be withdrawn and reinserted to make any 130

desired predetermined combination or that there may be as many pins 36, 37 as there are push-buttons, thus increasing the possible number of combinations. Of course if there 5 are more than two pins 36, 37 there must be more coöperating disks but I have found it to be sufficient to provide but two of such pins and disks, leaving the remainder of the push-buttons opposite blanks, thus increasing 10 the difficulty of one unfamiliar with the combination to hit upon the right one without actuating the bells.

Bell 46 may be located in the room, apartment or house where the device is located 15 and the other bell or bells in parallel therewith may be located in neighboring rooms, apartments or houses, thus giving the signals at different points. If it is desired to cut the device out of service for any reason, 20 switch 44 may be opened.

It is obvious that the bell crank 52 may be counterweighted so that after spring 53 has tripped it, it will fall back into neutral position and break the contact so that the bell 25 will stop ringing and the instrument may be reset and the door closed.

It is obvious that there may be many variations in arrangement and numbers of parts without departing from the broad idea of my 30 invention and I do not limit myself to the details as shown and described, further than the scope of the appended claims demand.

What I claim and desire to secure by Letters Patent is:

35 1. In an electric protective device, a switch element comprising a casing of non-conducting material provided with a plurality of openings through the face thereof, a spring controlled plate adjacent the inner face of said casing, push buttons mounted in said openings and bearing against said plate, a conducting piece carried by said plate and a second conducting piece in the path of said first conducting piece, said first and second conducting pieces being provided 40 with means for connecting them with signal circuit terminals.

2. In an electric protective device, a switch element comprising a casing of non-conducting material provided with a plurality of openings through the face thereof, a spring controlled plate adjacent the inner face of said casing, push buttons mounted in said openings and bearing against said plate, 50 pins carried by said push buttons and projecting through said plate, a conducting piece carried by said plate, a second conducting piece in the path of said first con-

ducting piece, a movable support of non-conducting material, a pin carried by said support in the path of one of said push buttons and its pin and bearing against said movable support, a third conducting piece carried by said movable support and a fourth conducting piece between said second 60 and third conducting pieces and insulated from said second conducting piece, said conducting pieces respectively being provided with means for connecting them with signal circuit terminals.

3. In an electric protective device, a switch element comprising a casing of non-conducting material provided with a plurality of openings through the face thereof, a spring controlled plate adjacent the inner face of 70 said casing, push buttons mounted in said openings and bearing against said plate, pins carried by said push buttons and projecting through said plate, a conducting piece carried by said plate, a second conducting piece in the path of said first conducting piece, a plurality of movable supports of non-conducting material arranged one behind the other, a pin carried by each 75 said support and bearing against said support, each pin in the path of a push button and its pin, a conducting piece carried by each said support and a conducting piece in the path of each of said movable conducting pieces but insulated from said second conducting piece, said conducting pieces respectively being provided with means for connecting them with signal circuit terminals.

4. In an electric protective device, a switch element comprising a casing of non-conducting material provided with a plurality of openings through the face thereof, a plurality of spring-controlled movable plates of non-conducting material arranged one behind the other opposite said openings, 95 push buttons seated in said openings for moving said plates away from the face of said casing, pins carried by said push buttons, conducting pieces carried by each of said plates and fixed conducting pieces in 100 the path of each of said movable conducting pieces, said conducting pieces respectively being provided with means for connecting them with signal circuit terminals.

In testimony whereof I have signed this 110 specification in the presence of two subscribing witnesses.

WILLIAM DEUTSCHER.
